A. H. BOLTZ

NUT LOCK

Filed Dec. 23, 1922

Inventor

A.H.Boltz

By Watson E. Coleman
Attorney

UNITED STATES PATENT OFFICE.

ARTHUR H. BOLTZ, OF TALLMADGE, OHIO.

NUT LOCK.

Application filed December 23, 1922. Serial No. 608,730.

To all whom it may concern:

Be it known that I, ARTHUR H. BOLTZ, a citizen of the United States, residing at Tallmadge, in the county of Summit and State 5 of Ohio, have invented certain new and useful Improvements in Nut Locks, of which the following is a specification, reference being had to the accompanying drawings.

This invention relates to nut locks, and 10 particularly to that class of nut locks wherein a key is used to lock the nut to the bolt.

One of the objects of the present invention is to provide a nut lock of this character which is very simple and effective in use and 15 which is so constructed that the application of a wrench to the nut automatically releases the locking engagement between the nut and bolt so as to permit the nut to be rotated, and wherein the removal of the wrench from 20 the nut causes the automatic locking engagement between the nut and bolt.

A further object is to provide a device of this character which uses what is practically an ordinary bolt and an ordinary nut 25 and requires but slight change in the nut and the bolt.

Other objects will appear in the course of the following description.

My invention is illustrated in the accompanying drawings, wherein:—

Figure 1 is an elevation of a nut and bolt with my improved nut lock applied thereto;

Figure 2 is an end view of the bolt and nut and the lock;

Figure 3 is a like view to Figure 2, but showing a wrench in section applied to the nut and the nut lock released from engagement with the bolt;

Figure 4 is a perspective view of the nut and bolt and nut lock.

Referring to these drawings, it will be seen that the bolt 10 is longitudinally grooved at 11 at a plurality of points. I have shown three grooves equi-distantly spaced from 45 each other and having a depth equal to the depth of the screw-threads 12, but I do not wish to be limited to this as it is obvious that more or less grooves might be used. Except for the fact that the bolt is grooved 50 at 11, the bolt is of any ordinary or suitable form.

The nut 13 is provided upon one of its lateral faces with a substantially U-shaped groove 14, the legs of the U-shaped groove 55 extending parallel to the axis of the nut and

each opening at one end upon the outer end of the nut. The transverse portion of the U-shaped groove is disposed closely adjacent the inner face of the nut.

Disposed within the U-shaped groove and pivotally supported therein is the latching or locking device which comprises, as illustrated in Figure 4, a resilient wire bent to provide a U-shaped portion 15 which is adapted to be disposed in register with the U-shaped groove 14. The cross bar of the U-shaped portion of this latch or lock is disposed over the transversely extending portion of the U-shaped groove 14, while the leg 16 of the wire is disposed in the arm 14^a 70 of the groove 14 and is held therein by an overturned portion 14^b. Beyond this leg 16 the wire is bent at right angles at 17 and then formed with an inwardly projecting terminal 18 which is adapted to engage in 75 any one of the grooves 11.

It will be seen from Figure 2 that the cross bar 19 of the U-shaped wire 15 is normally deflected outward from the face of the nut, while the arm 20 of the wire extends 80 longitudinally and inward and normally only bears at its outer end in the groove 14. The cross bar 19 forms one arm, therefore, of a crank, the body of which consists of the portion 16 of the wire, the other arm 85 of the crank being the arm 17.

Now when the end of the cross bar 19 is forced inward, this crank will be turned to carry the extremity 18 out of the groove 11. When pressure is relieved upon the outwardly projecting end of the transverse portion 19 of the wire, however, the resiliency of the arm 20 will cause the portion 19 to shift outward, which will carry the arm 17 inward and the terminal 18 into engagement 90 with the groove. Thus the terminal 18 is resiliently forced toward the bolt and will spring into a groove 11 when the terminal end 18 comes in register with the groove, but when it is desired to release the nut it is only necessary to press in on the outwardly projecting end of the transverse portion 19 of the wire and then the terminal end 18 will be withdrawn from the groove. Inasmuch as the arm 20 of the wire extends upward 95 and inward from the face of the nut and into the upper end of the groove 14, it will follow that when a wrench as, for instance, the wrench A is applied to the nut it will force the portion 20 inward into the cor- 105 110

responding portion of the groove 14 and force the transverse portion 19 into the corresponding portion of the groove and this will retract the terminal 18 from engagement with the bolt, thus releasing the lock. It will be seen that with this construction the application of the wrench to the nut releases the lock but that until the wrench is applied the nut is held in its locked position upon the bolt.

While I have illustrated a socket wrench A, obviously any other wrench which will press upon the transverse portion 19 of the locking device will release the nut lock, and under some circumstances and if the wire be sufficiently resilient, it is possible to press inward manually upon the transverse portion 19 and release the lock. It will be obvious that after the wrench is applied the nut may be screwed on or unscrewed without any attention being paid to the lock, which will remain released from engagement with the bolt so long as the wrench is applied to the nut.

While I have illustrated a particular embodiment of my invention, I do not wish to be limited thereto as it is obvious that many changes might be made in the details of construction and arrangement of parts without departing from the spirit of the invention as defined in the appended claims.

It will be seen that this nut lock is of very simple construction and that the bolt and nut and locking device can be constructed at a much less cost than with the bolt, nut and cotter pin now in use. At the same time a positive lock is secured which, however, does not prevent the ready removal of the nut at any time by the application of a wrench thereto.

I claim:—

1. The combination with a bolt having a longitudinally extending groove, of a nut engaging the bolt, the lateral face of the nut having a groove extending parallel to the axis of the nut, and means for locking the nut on the bolt comprising a wire having a portion disposed in the last named groove for oscillation around the axis of the portion, one end of the wire being bent at right angles and constituting a crank arm and extending over one end face of the nut and having a tooth to extend into the groove in the bolt, the opposite end of the wire being bent to form a crank arm extending in an approximately opposite direction from the first named arm and normally extending at a slight angle to the peripheral face of the nut, and resilient means urging said last named arm outward and the first named arm toward the bolt.

2. The combination with a bolt having a longitudinal groove, of a nut for engagement therewith, and a locking device em-

bodying a cranked portion, one end of which extends beyond one end face of the nut and is formed to provide a crank arm with a terminal end adapted to be inserted in the groove of the bolt, the other arm of the cranked portion normally extending at an angle to other end face of the nut, this cranked portion being oscillatably mounted upon the nut, the last named crank arm being extended toward the face of the nut and at right angles to the crank arm and being resilient whereby to cause the second named crank arm to be forced outward and the first named crank arm toward the nut.

3. The combination with a bolt having a longitudinally extending groove, of a nut engaging the bolt, the lateral face of the nut being formed with a U-shaped groove, and a locking device comprising a resilient wire bent to provide a member oscillatably mounted in one arm of said groove and two arms extending at right angles to each other from said member, one of said arms extending over one end face of the nut and having a terminal portion adapted to engage the groove, the other arm normally extending gradually outward from the lateral face of the nut and then inward and toward the end face of the nut and having the extremity of this portion engaging in one arm of said groove, inward pressure exerted upon this last named portion causing the oscillation of said cranked member and the withdrawal of the terminal end of the first named arm from said groove.

4. The combination with a bolt having a longitudinally extending groove, of a nut engaging the bolt, the lateral face of the nut having a groove extending parallel to the axis of the nut, and means for locking the nut on the bolt comprising a wire having a portion disposed in the last named groove for oscillation around the axis of the portion, one end of the wire being bent at right angles and constituting a crank arm and extending over one end face of the nut and having a tooth to extend into the groove in the bolt, the opposite end of the wire being bent to form a crank arm extending in an approximately opposite direction from the first named arm the last named arm having a portion resiliently engaging a side face of the nut.

5. The combination with a bolt having a longitudinally extending groove, of a nut engaging the bolt, the lateral face of the nut having a groove extending parallel to the axis of the nut, and means for locking the nut on the bolt comprising a wire having a portion disposed in the last named groove for oscillation around the axis of the portion, one end of the wire being bent at right angles and constituting a crank arm and extending over one end face of the nut

and having a tooth to extend into the groove end against a side face of the nut and in the bolt, the opposite end of the wire urging the second named arm outward and being bent to form a crank arm extending the first named arm toward the nut. 10
in an approximately opposite direction from the first named arm, the last named arm having a portion extending at right angles thereto and resiliently bearing at its upper

signature.

ARTHUR H. BOLTZ.
